PROJECTION DEVICE

Lawrence E. Reed, Washington, D. C.

Application June 13, 1935, Serial No. 26,474

5 Claims. (Cl. 88—24)

This invention relates to projection devices and has for its principal object the production of a simple and efficient means for facilitating the enlargement, the reduction, or the reversing 5 of a picture projected from the projection device.

Another object of this invention is the production of a simple and efficient means for facilitating the copying of a picture through the medium of a projection device whereby the picture may be thrown down upon a sheet upon 10 which the copy is to be made in a desired size and desired position.

A still further object of this invention is the production of a simple and efficient projection 15 device which may be known as a copy-composer, the parts of which are constructed so as to permit the device to be knocked down or collapsed.

Another object of this invention is the production of a simple and efficient means for facilitating the vertical adjustment of the projecting 20 cabinet with respect to the base;

Other objects and advantages of the present invention will appear throughout the following specification and claims.

25 In the drawings:—

Figure 1 is a perspective view of the projection device;

Figure 2 is a vertical sectional view through the projecting box or cabinet showing a portion 30 of the supporting standard;

Figure 3 is a vertical sectional view taken on line 3—3 of Figure 2;

Figure 4 is a horizontal section taken on line 4—4 of Figure 3;

Figure 5 is a rear elevation of the projecting box or cabinet showing a portion of the supporting standard;

Figure 6 is a vertical sectional view through the projecting cabinet illustrating the position 40 of the reflecting mirror for reversing the picture;

Figure 7 is a detail perspective view of one of the lid sections;

Figure 8 is a perspective view of the projection device showing the reflecting mirror in its angular position for reversing the picture before 45 projecting the image through the lens;

Figure 9 is a perspective view of the body of the projecting cabinet or box in a folded or collapsed position;

Figure 10 is a group perspective view of the end 50 lid sections;

Figure 11 is a perspective view of the bottom of the projecting box or cabinet;

Figure 12 is a perspective view of the lens tube;

Figure 13 is an enlarged transverse sectional view taken on line 13—13 of Figure 2;

Figure 14 is a plan view of the picture supporting panel.

By referring to the drawings, it will be seen 5 that 20 designates the base which is preferably of a flat panel-like structure having a rectangular socket 21 formed at one end intermediate its sides into which fits the lower end of the supporting standard 22, this standard being 10 locked in position by means of a locking screw 23. The supporting standard 22 is provided with a forwardly extending inclined portion 24 which terminates in an upright portion 25, and the standard 24 is preferably of a channel iron structure substantially U-shaped in cross-section. The upright portion 25 is provided with spaced notches 26 for the purpose of receiving the teeth 15 of the adjusting gear wheel 27 hereinafter described.

A projecting cabinet or box A is adapted to be supported upon the standard 22 and preferably comprises a rectangular structure constituting a back panel 28 and a front panel 29, these front and back panels 28 and 29 being hingedly connected to the end panels 30 whereby the box or cabinet A may be collapsed as shown in Figure 9 to be accommodated in a minimum amount of space for storage, shipment, or packing. The front panel 29 is provided with an offset compartment 32 directly opposite the compartment 20 of the rear panel 28.

A removable bottom 33 is adapted to fit over the lower edges of the panels or walls 28, 29 and 30, and to hold these panels in a set-up relation, 35 the bottom 33 having upstanding flanges 34 which flanges are provided with inwardly punched portions 35 for frictional engagement with the panels 28, 29 and 30 and for assisting in holding the bottom in position. The bottom 33 is provided with a centrally located depending annular flange 36 within which may be fitted the projecting lens tube 37 which tube may be detachably secured to the flange through the medium of a bayonet slot and pin connection. The 40 tube 37 may also be longitudinally slotted, as at 38, to permit the lens 39 to be adjusted for obtaining the proper focus. Lamp bulb sockets 46 are carried by the bottom 33 upon opposite sides of the annular flange 36 and support illuminating bulbs 41 which may be electrically connected to any suitable source of electrical supply through the wires 42.

Lid sections 43 are removably secured and fitted over the top of the box or cabinet A at 45

55

its respective ends, as shown in Figures 1 and 8, and these lid sections 43 are preferably perforated, as at 44, for ventilation purposes, the lid sections having depending flanges 45 which overlap upper edge portions of the side and end walls or panels of the cabinet. The flanges 45 are also provided with inwardly punched portions 46 similar to the punched portions 38 to assist in holding the lid sections 43 in place when fitting over the upper edges of the panels or walls 28, 29 and 30 when the box or cabinet A is in a set-up position. Each lid section 43 is provided with a triangular hinged plate 47, along its inner edge, which hinged plate is adapted to be swung at right angles to the lid section 43, each plate 47 having an angularly extending flange 48 along its inclined side and also being provided with a ledge portion 49 along its upper edge adjacent the hinge 50. Each plate 47 is also provided with spring tongues 51 along its straight edge portion which portion is adapted to normally lie close to the rear panel 28 when the lid sections 43 are placed in a set-up position. When the lid sections 43 are fitted over the top of the cabinet or box A adjacent its respective ends and when the cabinet is in a set-up position, the flange 48 of each plate 47 of each lid section 43 will incline downwardly from the top of the lid section 43 away from the front panel 28 and toward the rear panel 28.

An operating shaft 52 is journaled upon the rear face of the rear panel 28 and supports the gear wheel 27, which gear wheel meshes with the sockets 26, the sockets 26 constituting a rack. The shaft 52 carries a crank 53 and by swinging the crank 53, the shaft 52 will be rotated thereby causing the gear wheel 27 to move the box or cabinet A upwardly or downwardly depending upon the direction of rotation of the shaft 52. In this way, a proper vertical adjustment may be provided for the box or cabinet A with respect to the base 20 to obtain the approximate proportion of enlargement desired.

In carrying out my invention I preferably place a mirror 54 in a vertical position within the offset compartment 31 of the rear panel 28, the spring tongues 51 engaging the sides of the mirror 54 and holding the same in a set position—note Figure 13. I also provide a picture-supporting panel 55 having a finger tab 56 at one end and carrying picture-supporting clips 57 for supporting the picture or card 58 containing the illustration which is to be enlarged,—note particularly Figure 14. When it is desired to enlarge and reverse the picture as shown in Figure 14, the picture 58 is placed upon the panel 55 and secured in position. This panel is then placed with the picture 58 face downward so that the edges of the panel 55 may rest upon the shoulders 48 of the plates 47—note Figures 1 and 3. The finger tab 56 of the panel 55 will extend forwardly so that the panel may be easily handled and the picture 58 will appear in a proper position. The mirror 54 when the parts are in this position is of course inactive being in a vertically extended position. The light from the lamps 41 will illuminate the interior of the cabinet A and the image will be focused through the lens 39 and cast down upon the sheet 59 which may be secured in any suitable or desired manner to the upper face of the base 20. The image will then appear as illustrated in Figure 1 enlarged upon the sheet 59 but facing in an opposite direction or in a reverse position.

When it is desired to have the image appear

in the same position and facing in the same direction, as the picture which is being enlarged, the panel 55 is placed in the position shown in Figure 8 within the front compartment 32 standing in a vertical position, and the mirror 54 which is hinged, as at 50, is swung to an inclined position so that the same may rest upon the inclined flanges 48. The image from the picture 58 then will be reflected upon the mirror 54 and down through the lens 39, and will be cast upon the sheet 59 as shown in Figure 8, facing in the same direction as the picture 58 as it appears upon the panel 55. In other words, when a reverse picture is desired, the panel 55 is rested upon the ledge portions 49 and the mirror 54 is positioned in an inactive vertical position, the picture 58 facing downwardly, but when a reverse picture is not desired, but it is desired to cast an image in the same position as the picture itself, the panel 55 is placed in a vertical position within the compartment 32, and the mirror 54 is swung to an inclined position resting against the supporting flanges 48—note Figure 6.

By noting Figure 5, it will be seen that the rear panel 28 is provided with an offset channel portion 25 in which fits the upper portion 25 of the standard 22 to constitute a track-way for connecting the cabinet or box A with the vertical portion 25 of the standard 22.

From the foregoing description, it will be seen that a very simple and efficient device has been produced in the nature of a projection device for throwing a reflection or image of a picture upon a sheet of paper in order that said picture may be traced upon said sheet. This device as stated above, is so arranged that a picture may be enlarged, reduced, or thrown into reverse. By throwing the picture in reverse it will be obvious that the picture may be thrown or traced facing in the opposite direction. Through the medium of the present device a picture post-card, magazine picture, or other object may be thrown or reflected upon a sheet of drawing paper for copying purposes in the manner as illustrated in Figures 1 and 8.

This device may be used commercially and may be built on a large scale for the purpose of making posters or other pictures, or for producing a number of copies of the same. The device is especially useful in schools, clubs, and the like, where it is desired to place an illustration or figure on a mimeograph for running off several copies.

The device may also be used as a toy for teaching drawing and a picture for example may be cast on a drawing sheet for copying purposes, enlarged or reduced as desired and drawn on the paper below, and if desired, an image or figure may be cast upon the drawing sheet for copying purposes and then subsequently a rural scene may also be cast for adding the scene to the picture being drawn. The picture may be varied merely by reversing the position of the figure to illustrate the figure going toward or away from the scene. The scene, as well as the image of the figure, may be enlarged or reduced to give the desired effect, and it is necessary of course when composing by using two or more pictures that the eye level of each picture be placed on the same line so that when the composite picture is finished, a proper perspective will be presented. In other words, the background may be made large or small to give the effect of its being close

at hand or far away, and hence the device may be used for teaching children or students certain fundamentals of art as well as providing pleasure in copying pictures as they originally stand.

It should be understood that the device has considerable latitude in permitting the combination of a number of different elements to provide a composite picture by allowing the different elements to be cast upon the drawing sheet at different periods, and in this way permitting the addition from time to time of certain elements of the picture to provide a desired composite scene or pictorial illustration.

Certain detail changes in the mechanical construction, combination and arrangement of parts may be employed without departing from the spirit of the invention, so long as such changes fall within the scope of the appended claims.

I claim:

1. A projection device comprising a projecting cabinet, means for projecting an image from said cabinet and located in the bottom portion of the projection position, an image-reversing mirror within said cabinet at one side thereof hingedly mounted at its lower end for movement from a vertical position to an inclined position over the projecting means, an object carrier removable from said cabinet, means to support the carrier in a vertical position facing the mirror, means for supporting said reflecting mirror at an incline to the optical axis of the projecting means and at an incline to the center of the object carrier, and means to support the carrier in a horizontal position over the projector and at right angles to the mirror when the mirror is in a vertical position and in optical alignment with the projecting means.
2. A projection device of the class described comprising a cabinet, a projecting lens carried by said cabinet and located in the bottom portion of the cabinet in a projection position, said cabinet having portions of its front and rear walls offset outwardly to form pockets each open at its top and inner side, an object-supporting panel adapted to removably fit within one of said compartments whereby said panel may stand in an upright position, a reflecting mirror fitting into the other pocket and pivoted at its lower end, means for supporting said reflecting mirror at an incline to the optical axis of the projecting means and at an incline to the center line of the object-supporting panel to cause the reflection of an image through said lens in reverse, and means to support the panel in a horizontal position over the lens and at right angles to the mirror and in optical alignment with said projecting means when the mirror is in the upright position.
3. A projection device of the class described comprising a cabinet, a projecting lens carried by said cabinet and located in the bottom portion of the cabinet in a projection position, said cabinet having vertically extending compartments in its front and rear portions, an object-supporting panel removably supported by said cabinet and adapted to removably fit within one of said compartments whereby said panel may stand in an upright position, a reflecting mirror carried by

said cabinet, said cabinet having spaced removable lid sections for closing end portions of its top and providing an opening therebetween, each lid section having a depending triangular portion provided with a longitudinally extending panel supporting ledge upon which ledge said panel may rest in a horizontal position at right angles to the mirror and in optical alignment with said projecting lens, and said triangular portions having inturned flanges to provide supports for said mirror whereby said mirror may be supported on an incline within said cabinet and at an incline to the optical axis of the projecting lens and at an incline to the center line of the object-supporting panel when the panel is fitted into the said compartment of the cabinet.

4. A projection device of the class described comprising a cabinet, a projecting lens depending from said cabinet, said cabinet having vertically extending compartments in its front and rear portions, an object-supporting panel removably supported by said cabinet and adapted to removably fit within one of said compartments whereby said panel may stand in an upright position, a reflecting mirror carried by said cabinet, the mirror being hinged at its lower end for movement from a vertical position in the other compartment to an inclined position over the projecting lens, said cabinet having lid sections for closing end portions of its top, each lid section having a depending triangular portion provided with a longitudinally extending panel supporting ledge upon which ledge said panel may rest in a horizontal position, said triangular portions having inturned flanges to provide supports for said mirror whereby said mirror may be supported at an inclined position within said cabinet, and said triangular portions having spring clips for engaging the edge of said mirror to hold the mirror in a vertical inactive position.

5. A projection device of the class described comprising a cabinet, a projecting lens depending from said cabinet, said cabinet having portions of its front and rear walls offset to form vertically extending compartments in its front and rear portions, an object-supporting panel adapted to removably fit within one of said compartments whereby said panel may stand in an upright position, a reflecting mirror carried by said cabinet in the other compartment and hinged at its lower end for movement out of the compartment to a position across the cabinet at an incline to cause the reflection of an image through said lens in reverse, said cabinet having lid sections for closing end portions of its top, each lid section having a depending triangular portion hinged thereto and provided with a horizontally extending panel supporting ledge upon which ledge said panel may rest in a horizontal position when the mirror is upright in its compartment, said triangular portions having inturned flanges along their lower edges to provide supports for said mirror when the mirror is in the inclined position, said triangular portions having spring clips for engaging side edges of said mirror to hold the mirror in a vertical position within its compartment.

LAWRENCE E. REED.
